UNITED STATES PATENT OFFICE.

SAMUEL T. EVANOYE, OF SEATTLE, WASHINGTON.

LIQUID SLOT MACHINE.

Application filed February 6, 1924. Serial No. 690,923.

The invention is a slot machine which may be operated by a coin and which will first deliver a cup and then a predetermined amount of liquid to fill the cup.

5 The object of the invention is to provide a means whereby a given amount of liquid may be obtained from a container with a coin.

Another object of the invention is to provide 10 a device whereby drinking cups may be ejected from a container by turning a handle after a coin has been placed therein.

And a further object of the invention is to provide a small container which has suitable valves for permitting a liquid to flow 15 through it, in which the valves which will be locked may be released by a coin.

And a still further object of the invention is to provide a small container for measuring 20 and releasing a given amount of a liquid in which the amount of the liquid that will be measured by the container may be regulated.

With these ends in view the invention embodies a container for liquids or the like having a small compartment in it in which a cooling substance may be placed and a coin chute attached to it which will operate a device for ejecting cups as a coin passes 25 downward in it and also a means for ejecting a predetermined amount of the liquid in the container as the coin reaches the lower end.

Other features and advantages of the invention will be seen from the following description taken in connection with the drawings, wherein:

Figure 1 is a front view with part broken away.

Figure 2 is a plan view with parts omitted.

40 Figure 3 is a sectional view showing the paper cup ejecting roll and also the means for locking and releasing the liquid measuring device.

Figure 4 is a cross section through the liquid measuring device.

In the drawings I have shown my device as it would be constructed wherein numeral 1 indicates a keg, numeral 2 a casing for holding small cups, and numeral 3 a liquid 50 measuring device.

The keg 1 may be of any suitable design or may be constructed in the form of a tank or any suitable container and may be made integral with the casing or detachable as shown. A secondary container 4 may be

placed in the center of the keg so that ice or any suitable material for cooling the liquid in the keg may be placed in it. The container 4 may have a drain pipe 5 leading from its lower end through an opening 6 in the outer wall of the casing to a cock 7 by which the container may be drained. This inner container may also be of any shape or design and may be made integral with the keg or detachable.

65 The outer casing 2 may have a coin chute 6 at one side which is provided with an opening 7 at the upper end into which coins may be placed. A lever 8 which is pivoted on a pin 9 in the casing 2 may project into the chute 6 as shown in Figure 1 so that a coin will engage its inner end as it passes downward and it will be seen that the weight of the coin will force the inner end of the lever 8 downward and the outer end 11 upward to the position shown in dotted lines 70 in Figure 1. The chute may be provided with an opening 12 so that the coin, which I have indicated by dotted lines 13, may engage the surface of a disc 14 on a shaft 15.

80 which will hold the coin between the face of the disc and the end of the lever 8. The end 11 of the lever 8 operates between guides 16 and fits into a notch 17 in a disc 18 so that it will normally lock the disc and prevent the turning of a handle 19 on the end of the shaft 15 upon which the disc 18 is also fixedly mounted. However, when a coin arrives at the position shown in dotted lines 85 and indicated by the numeral 13 the end 11 of the lever 8 will raise and permit the handle 19 to be turned. As soon as the handle is turned a recess 20 in the disc 14 will permit the coin to move slightly outward and release the lever 8 and then drop 90 downward into the chute. The handle 19 may then be turned in a complete revolution and as it is turning it will rotate a roller 21 which is also mounted on the shaft 15 and as this roller frictionally engages another 100 roller 22 which is rotatably mounted in the casing on the shaft 23 it will cause this roller to rotate and move a strip 24 containing paper cups outward through an opening 25 in the side of the casing. The strip 24 may be constructed by attaching the paper 105 cups to a strip of material which may be perforated at intervals so that they may readily be torn off or may be especially made by making a series of paper cups into a strip 110.

with perforations between them. This strip may be wound upon a roller 26 which may be rotatably mounted in the casing on a shaft 27. It will be seen that as the handle 19 is rotated it will rotate the roller 21 and this roller may be of such a size that it will cause the strip to move outward a distance of only one cup. As the handle completes its revolution the end 11 of the lever 8 which is considerably heavier than the end 10 will drop into the notch 17 in the disc 18 and again lock the handle.

As the coin drops downward it will engage an end 28 of a lever 29 which extends 15 into an opening in the edge of the chute 6 and which is pivotally mounted on a pin 30 in bearings 31 in the lower part of the casing and as it engages this end of the lever its weight will force this end downward 20 and the opposite end 32 upward so that the shoulder 33 will move away from a shoulder 34 on a projection 35 of the operating lever 36. The lever 36 is provided with a knob 37 at its outer end by which it may 25 be pulled outward and a spring 38 at its inner end which will pull it inward and return it to its normal position. This lever is provided with an extension 39 that projects through a slotted hole 40 in the lower 30 section 41 of the container 3 and on the extension 39 is a plate 42 which slides with the lever 36 and closes the inner end of the opening 40 at all times. The plate 42 is provided with a projection 43 which has attached to it a flat plate 44 that will slide on the bottom of the container and close an opening 45 therein when the device is not 35 in use. The opening 45 extends downward through a tubular shaped casing forming a spout 46 through which the liquid will pass when it is being taken from the container. The projection 43 of the plate 42 is also provided with a small rod 47 that extends through the tubular shaped casing 48 at the 40 inner end of the section 41 and is pivotally attached to a cover plate 49 which is hinged to the inner end of the casing 48 as shown at the point 50 in Figure 2. The casing 48 is held to the keg or container 1 by placing the casing 48 through an opening in the lower part of the keg and locking it in place by screwing a nut 51 on the inner end of the casing. The nut 51 will lock the wall of the container against a shoulder 52 on the 45 casing 48 as shown in Figure 4. The upper section 53 of the container 3 may be constructed as shown and provided with a diaphragm 54 having a set screw 55 in its center so that the diaphragm may be raised or 50 lowered to increase or decrease the volume on the interior of the container 3, so that it will be possible to regulate the amount of liquid that will be ejected from the container 3. The sections 41 and 53 may be held together by screws 56 or any other suit-

able means. The end of the projection 35 of the lever 36 is provided with another extension 57 which extends backward to the chute 6 and this extension is provided with guide plates 58 and 59 which will move 70 from the position shown in Figure 2 to a position directly under the chute 6 so that the coin will pass through an opening in the edge of the chute 6, between the guides, and then drop into an opening 60 in the casing. 75 A door 61 may be placed in the rear of the casing and may be provided with a lock 62. The casing may also be provided with a cover 63 which may be hinged at the point 64 and held at the opposite side by a lock 65 so that it may readily be opened when it is desired to examine or repair the mechanism on the interior.

It will be understood that changes may be made in the construction without departing from the spirit of the invention. One of which changes may be in the arrangement or design of the coin chute; another may be in the type or design of the paper cups, or in the means for ejecting them; and still another change may be in the design or arrangement of the means for measuring and ejecting the liquid.

The construction will readily be understood from the foregoing description. To use the device it may be constructed as shown and it will be seen that as the coin is placed in the opening 7 the handle 19 may be turned which will eject a cup as hereinbefore described. The coin will then release the lever 36 and when the knob 37 is pulled outward the coin will be permitted to pass between the guides 58 and 59 and into the box below as hereinbefore described. It will be seen that in the normal position the coin will engage the guide 59 and be held in the chute and on the end 28 of the lever 29.

As the lever 36 moves forward the plate 44 will also move forward and open the opening 45 so that liquid in the container 3 may pass out of the spout 46, and at the same time the rod 47 will close the inner end of the casing 48 by drawing the cover 49 against it and thereby prevent liquid in the large container passing into the measuring device, and as the knob 37 is released the plate 44 will move back to the position shown on the drawing so that it will close the opening 45 and the rod 47 will open the cover at the inner end of the tubular casing 48 so that the measuring device may be again filled with liquid from the container. At the same time the end 28 of the lever 29 will move upward and the heavier end 32 will drop downward and lock the lever 36 so that it will be impossible to obtain any additional liquid from the device until another coin has been placed in the slot.

Having thus fully described the inven-

tion, what I claim as new and desire to secure by Letters Patent, is:—

In a liquid dispenser, a container, means for varying the effective capacity of said container, comprising a flexible diaphragm, said container having an inlet opening in one wall, an unaligned outlet opening in a wall adjacent but not parallel to said first wall, valve means for each of said openings,

rigid connections between said valve means for holding one valve open when the other is closed, resilient means for holding the valve means in one position, a handle for manually operating the valve means and suitable means for locking the said valve means in one position until it is released by a coin. 10

SAMUEL T. EVANOYE. 15
